REMOVABLE LETTER SIGN

Werner I. Staaf, Rennerdale, Pa.

Application April 13, 1948, Serial No. 20,670

2 Claims. (Cl. 40—140)

1

This invention relates to letter display signs, and is for a sign for the display of letters, numerals and other display characters in which the letters or display elements are firmly held, but into which they may be readily inserted, and easily removed for cleaning or replacement.

My invention has for its object to provide a sign with a sign bar of novel construction, which is simple and economical to manufacture, and in which the letters will be tightly held.

My invention is characterized by the provision of a bar, preferably extruded from aluminum or other light metal having closely spaced flanges. Between these is a spring metal strip secured to one of the flanges and yieldably pressing against the other. The letters or like display characters are provided with tabs which are inserted between the spring and the flange toward which the spring is urged.

My invention may be more fully understood by reference to the accompanying drawings, in which:

Fig. 1 is a perspective view of the sign bar, the bar being shown in section; and

Fig. 2 is a similar view to Fig. 1 on a smaller scale showing some letters in place and viewing the sign bar from the opposite face.

In the drawings, 2 designates the bottom flange or web of an angle-shaped sign bar having a front upright flange 3. There is a second upright flange 4 parallel with the flange 3 and spaced a slight distance to the rear of it. Near the base of the rear flange 4 at intervals therealong are holes 5. The sign bar is preferably formed of extruded aluminum or other light metal. Hence it may be quite cheaply formed in any desired length and is of good appearance.

Fitted over the flange 4 is a resilient metal strip of clip form having an inverted U-shaped portion 6 that snugly fits the top edge of the flange 4. One leg of this strip projects down between the flanges 3 and 4 and is bowed outwardly to contact the inner face of the flange 3 and then curves back toward the flange 4 at its lowermost edge. This resilient bowed leaf spring portion of the clip is designated 7. The other leg 8 of the U-shaped strip extends down over the rear face of the flange 4 and it partly covers the holes 5. Where the leg 8 passes over the holes 5, it is pressed inwardly, as indicated at 9, so as to interlock the strip with the flange and restrain it from endwise movement or from transverse or upward movement. Strip stainless steel is preferably used for this purpose.

The letters or other display figures, designated 10, may be of various forms. I have shown them formed of embossed sheet metal. They are provided with flat extensions or tabs 11. These tabs are forced down into the space between the two flanges and they are frictionally engaged by the bowed spring 7. The tabs are forced down until

2

the lower edge of the letter or other display contacts the top edges of the upstanding flanges.

The spring clip is substantially co-extensive with the sign bar. The flange 2 provides a convenient base that may be rested on and secured to a supporting ledge, brackets, or the like. The assembled sign is light and easy to handle and install. The letters, while being easily inserted, are firmly gripped and will not dislodge even if the sign be turned upside down. However, if they be gripped and pulled in a proper manner, they can be easily taken for rearrangement or change. The sign is attractive, inexpensive and convenient.

While I have shown letters in the sign, other characters or figures may be used. The letters or other display characters may be of metal, plastic, or other material. If made of wood the metal tabs are separately secured thereto.

While I have shown and described a specific embodiment of my invention, various changes and modifications may be made therein.

I claim:

1. A sign bar comprising an angle-shaped metal section with a base flange and an upright flange, the upright flange being comprised of parallel spaced webs one of which is directly in front of the other, and an inverted U-shaped leaf spring resiliently engaged over the rear web and having the leg of the U which is between the two webs bowed outwardly from the plane of the rear web toward the front web.

2. A sign bar comprising an angle-shaped metal section with a base flange and an upright flange, the upright flange being comprised of parallel spaced webs one of which is directly in front of the other, and an inverted U-shaped leaf spring resiliently engaged over the rear web and having the leg of the U which is between the two webs bowed outwardly from the plane of the rear web toward the front web, the rear web having holes near the base thereof at intervals therealong, the rear leg of the inverted U-shaped spring being de-formed into said holes to interlock the spring with the web.

WERNER I. STAAF.
